CHARLES F. MOSMAN, OF BRIDGEPORT, CONNECTICUT, ASSIGNOR TO
ANDREW KROUSE, OF SAME PLACE.

DESIGN FOR A PICTURE-FRAME.

SPECIFICATION forming part of Design No. 23,751, dated October 30, 1894.

Application filed May 17, 1894. Serial No. 511,614. Term of patent 3½ years.

To all whom it may concern:

Be it known that I, CHARLES F. MOSMAN, a citizen of the United States, residing at Bridgeport, in the county of Fairfield and State of Connecticut, have invented and produced a new and original Design for Frames for Pictures and the Like, of which the following is a specification, reference being had to the accompanying illustration, which fully represents the nature and features of my design.

The leading features of my design consist in the representations of a flaming lamp at the top of the frame, an owl seated upon a crescent at one of the upper corners of the

frame, and the general combined beaded and foliate patterns which appear in the drawing.

1 is the flaming lamp, 2 the owl seated upon the crescent, and 3, 4, the beaded and foliate patterns respectively.

I claim—

The design for picture frames substantially as shown in the accompanying drawing.

In testimony whereof I affix my signature in presence of two witnesses.

CHARLES F. MOSMAN.
